W. F. WICKERSHAM AND ELISHA ROUSH, OF SPRINGFIELD, ILLINOIS.

Letters Patent No. 77,150, dated April 21, 1868.

IMPROVED CAR-COUPING.

The Schedule referred to in these Letters Patent and making part of the same.

TO ALL WHOM IT MAY CONCERN:

Be it known that we, W. F. WICKERSHAM and ELISHA ROUSH, of Springfield, in the county of Sangamon, and State of Illinois, have invented a new and improved Car-Coupling; and we do hereby declare that the following is a full, clear, and exact description thereof, which will enable others skilled in the art to make and use the same, reference being had to the accompanying drawings, forming part of this specification.

This invention relates to a new and improved method of constructing the coupling of railway-cars, whereby the same are more certain in their operation, and cars are coupled more quickly, and without danger.

It consists in a gate, pivoted within the buffer by a pivot passing through a slot in the same, whereby the same is both raised and swung backward upon the introduction of the link into the buffer, the said gate dropping behind a shoulder near the end of the link.

It consists also in the rod passing through the buffer, and through a slot in said link, said rod being provided with an arm, which, resting upon said gate, serves to make the coupling more secure.

In the accompanying plate of drawings—

Figure 1 is a central vertical longitudinal section of my invention.

Figure 2 is a plan view of the link.

Figure 3 is a side view of the pin or rod.

Similar letters of reference indicate corresponding parts.

A are the buffers. B is the link. C is the gate. D is the rod or pin. a is an arm on the same. a' is the pivot on which the gate C moves. e is a cord attached to the gate.

The buffers A are made of the same material, and in the same general form as the buffers now commonly in use, having a mouth with all the sides inclined inwards, so as to receive and direct the link B, as shown in the drawing, fig. 1.

Through the upper and lower parts of each of the buffers A, at a short distance from the mouth of the same, or at about the distance therefrom of the pin now commonly in use, are square holes, to receive the pin or rod D, as shown, and so as that said rod D will stand in a vertical position, so as to pass through the slot-link B, as shown. The rod D may be made of iron, or other suitable material, of such length as to reach the top of the car, and so that the same may, at any time, be quickly withdrawn. The rod D is made square in form, so as to fit the square holes in the buffer A, and so as that said rod D will not turn in said holes, and is provided, on the back side of the same, with a metallic arm, a, of sufficient length to extend back, so as to rest upon the top of the gate C, so as to stop said rod from falling through the buffer A, and at the same time, by the weight of said rod D, prevent the gate C from lifting up. The arm a is either a part of said rod D, or is rigidly secured thereto in such position as to allow the rod D to extend entirely through both of the buffers A, as shown.

Back of the rod D, and through a mortise or slot in the upper part of the buffer A, is pivoted the gate C. The gate C is a solid iron block, rectangular in form, of any convenient size, so as to give the necessary strength and weight, as of the length of about three and one-half inches, and of the width of about two and one-half inches, and of the thickness of about two inches.

Said gate C is provided with and entirely through the same, near the top, with a slot, to receive the pivot or pin a', as shown, the said slot being of sufficient length, so as to allow of the gate C being raised, so as to allow the link to slip out when necessary, for the uncoupling of the cars, a cord, e, being attached to the upper part of the gate C, by means of which the same is raised when necessary.

The link B is made of iron, and is provided with a slot, to receive the rod D, and allow of sufficient play upon the same.

Said link is rounded off at each end, so as to allow the same to enter the mouth of the buffer A, and is provided with an upward projection on each end, so as to form shoulders behind which to receive the gate C, as shown, the distance between either end of the said slot and the shoulder on the same end of the link B being

exactly the same as the distance from the back side of the rod D to the back side of the gate C, as shown, so that the draught will be upon both the rod D and the gate C.

The operation is readily seen, there being a buffer, with gate and rod, upon each end of every car, the link being one for each pair of buffers, and, by making the link sufficiently narrow, said link will, when turned upon its edge, and the rod D is removed, slip out from the buffer, and the cars will be disconnected—an important feature when, by any accident, a forward car is thrown from the track, and tipped over.

We claim as new, and desire to secure by Letters Patent—

The combination of the rod or pin D, gate C, link B, buffer A, pivot a', and arm a, substantially as shown and described, and for the purpose set forth.

W. F. WICKERSHAM,
ELISHA ROUSH
